CLAIM

The ornamental design for a massage chair with kiosk display and partition, as shown and described.

DESCRIPTION

FIG. 1 is a front right perspective view of a first embodiment of a massage chair with kiosk display and partition; FIG. 2 is a front view of the massage chair shown in FIG. 1;

FIG. 3 is a rear view of the massage chair shown in FIG. 1; FIG. 4 is a left side view of the massage chair shown in FIG. 1;

FIG. 5 is a right side view of the massage chair shown in FIG. 1; FIG. 6 is a top view of the massage chair shown in FIG. 1; and

FIG. 7 is a bottom view of the massage chair shown in FIG. 1.

FIG. 8 is a front right perspective view of a second embodiment of a massage chair with kiosk display and partition; FIG. 9 is a front view of the massage chair shown in FIG. 8;

FIG. 10 is a rear view of the massage chair shown in FIG. 8;

FIG. 11 is a left side view of the massage chair shown in FIG. 8;

FIG. 12 is a right side view of the massage chair shown in FIG. 8;

FIG. 13 is a top view of the massage chair shown in FIG. 8; and,

FIG. 14 is a bottom view of the massage chair shown in FIG. 8.

The stipple shading is used to indicate wood panels. The evenly spaced dash-dot broken lines shown in the drawings are for illustrating portions of the article that form no part of the claimed design.

1 Claim, 14 Drawing Sheets
